By his Atty, J. G. Steuart -

United States Patent Office.

ANTHONY ZINK, OF LANCASTER, OHIO.

Letters Patent No. 91,196, dated June 8, 1869.

IMPROVEMENT IN PROPELLING-APPARATUS.

The Schedule referred to in these Letters Patent and making part of the same.

To all whom it may concern:

Be it known that I, ANTHONY ZINK, of Lancaster city, county of Fairfield, and State of Ohio, have invented a new and useful "Endless-Chain Propeller for Steamships and Boats;" and I do hereby declare the following to be an exact description thereof, reference being had to the accompanying drawings, and to the letters of reference marked thereon, making a part of this specification, in which—

Figure 1 represents a longitudinal sectional elevation of the propeller.

Figure 2, a top view of the one-half of the propeller.

Figure 3 shows a perspective view of a paddle and part of the endless chain, to show how they are connected.

A is a frame-work, to support the revolving cylinders B, that carry the endless chain C, with its upright arms D, axles E, and adjustable paddles G.

The frame-work A is intended to be permanently built on each side of a vessel.

The journals of the revolving cylinders B B operate in the sides of the frame or guards A, one of the cylinders B operating in boxes H H, that have slots, with screws J J in their centre, so that the cylinder B may be shifted back or forward, to tighten the endless chain, or slacken it, when required.

On each side of the cylinders B B are scalloped wheels K K, in which the joints of the links of the chain C fall, and are carried half around each wheel, giving the chain a continuous motion.

The links O are nutted and bolted together at their ends, so as to be easily repaired, and another replaced when one of the links becomes worn or broken.

The upright arms D D are also intended (see fig. 3) to be fastened to each link C by bolts and nuts, so that when one of the arms breaks, another can be quickly attached.

These arms D serve to brace each side and end of the paddle G, and strengthen it when moving on a line; but as the arms pass around the scalloped wheel K, the paddle continues resting upon the lower arm that opens with the angle of the link C, and again closes upon the paddle (as the paddle strikes the water) in unison with the next arm, both arms D D again uniting to strengthen the paddle G.

The paddles G are attached to braces L L by screw-bolts and nuts, so as to be adjusted for shallow or deep water, the braces being pivoted to the axles E, so that the paddles can move to and fro with the opening and closing of the arms D D; and in case a paddle breaks, it can be easily replaced by a new one.

What I claim as my invention, and desire to secure by Letters Patent, is—

The adjustable arms D D, that protect the paddle on each side, as herein described, and for the purposes set forth.

A. ZINK.
